UNITED STATES PATENT OFFICE

2,336,011

STEAM GENERATOR

Alfred H. Haberstump, Detroit, Mich., assignor to
The Murray Corporation of America, Detroit,
Mich., a corporation of Delaware

Application August 8, 1941, Serial No. 406,031

13 Claims. (Cl. 219—38)

My invention relates to steam generating devices, and particularly to a device which generates steam for heating, humidifying, sterilizing, and the like.

The present invention pertains to a steam generating device comprising a floating element having thereon immersible pairs of conductors which when joined to an electric circuit heat the water to produce steam. The device may be employed in the well of a radiator to produce steam for heating a room, or may be employed in the base of a container for producing steam for humidifying the room, or for sterilizing instruments, or steaming other articles, and other like uses. The element is so mounted in the container as to be bodily removable as a unit from the wall thereof for repair or replacement.

The unit may be supported on pivoted arms to retain the device in floating position and a weight element on the arms may be adjusted for regulating the depth at which the conductors project within the water to control the amount of current used and the amount of steam produced. Vertical pins may be employed for retaining the device in position when floating on the water and means may also be provided for relieving any excess pressure which may develop within a closed container. The device may be formed of spaced bars with alternate bars connected at opposite ends to one or the other leads of a circuit. The conductors may be made of bare wire disposed in parallel relation and wound spirally to have alternate conductors of like leads.

Accordingly, the main objects of my invention are: to provide a device for generating steam formed of spaced conductors which are insulated from each other and alternately disposed and floated to project a predetermined distance within the water; to form a device from spaced conductors which are alternately disposed and mounted on a floating element which regulates the depth to which the conductors project into the water on which the device floats; to provide weight which may be adjusted to change the degree of immersion of the conductors; to form a radiator of a plurality of intercommunicating sections in the base of which the device is mounted which produces steam upon the immersion of the conductors with the water upon which the device floats; to form a cabinet for receiving elements to be steamed or in which steam may be generated for the purpose of humidifying a room, having a device floated in the water in the bottom of the cabinet for immersing conductors supported thereby and which may be re-

moved as a unit from the cabinet; and in general, to provide a steam generating device which is simple in construction, positive in operation and economical of manufacture and use.

5 Other objects and features of novelty of my invention will be either specifically pointed out or will become apparent when referring, for a better understanding of my invention, to the following description taken in conjunction with 10 the accompanying drawings, wherein:

Figure 1 is a broken view, in elevation, of a radiator having a steam generating device there-in embodying features of my invention;

Fig. 2 is an enlarged sectional view of the structure illustrated in Fig. 1, taken on the line 2—2 thereof;

Fig. 3 is an enlarged sectional view of the structure illustrated in Fig. 1, taken on the line 3—3 thereof;

20 Fig. 4 is an enlarged sectional view of the structure illustrated in Fig. 3, taken on the line 4—4 thereof;

Fig. 5 is an enlarged sectional view of the structure illustrated in Fig. 3, taken on the line 25 5—5 thereof;

Fig. 6 is a view of structure, similar to that illustrated in Fig. 1, showing a further form of my invention;

Fig. 7 is a broken plan view of the structure 30 illustrated in Fig. 6, as viewed from line 7—7 thereof;

Fig. 8 is a view of structure, similar to that illustrated in Fig. 6, showing a further form which my invention may assume;

35 Fig. 9 is a plan view of the steam generating device illustrated in Fig. 8, as viewed from the line 9—9 thereof; and,

Fig. 10 is a sectional view of a steam generating device employed as a humidifier, sterilizer, 40 or the like.

Referring to Figs. 1 to 5, I have illustrated a radiator 12 made from a plurality of units which are welded or otherwise secured together and supplied with a steam generating unit 13.

45 The radiator is formed from a plurality of stampings, the stamping 14 of pan shape forming the top element enclosed by a partition 15 having an edge flange 16 which is seam welded or otherwise secured to the edge of the stamping 14. One or more openings 17 are provided in the partition 15 having a flange 18 thereabout which projects into a flange 19 on the next adjacent pan-like element 21. The flanges 18 and 19 are secured together by hydrogen welding or by other suitable methods and a partition 15 is secured

to the open face thereof. The flange 18 of the partition is secured to the next adjacent pan-like element 21 and the height to which the radiator is built is controlled by the number of partitions 15 and elements 21 which are secured together.

At the bottom of the assembly, a pan-like element 22 is secured to the flange 18 in the lowermost partition 15 and a bottom element 23 having a flange 24 at its edge is welded to the edge of the pan-like element 22. End stampings 25 are assembled over the ends of the elements 14, 21, and 22 and are welded thereto. Projecting leg portions 26 are formed in the bottom of the stampings 25 to provide a support for the element. It will be noted that the web of the pan portion 21 and the partition 15 slant upwardly from the rear face of the radiator to provide a convection flow of air between the sections toward the front of the radiator. The end wall in the pan-shaped element 22 is provided with an opening 47 sufficiently large to permit the steam generating device to be withdrawn therethrough.

The steam generating device 13 embodies an elongated float element 28 comprising a pair of stampings 29 semicircular in section, having outwardly projecting flanges 31 which are welded, brazed, or otherwise secured together. A pair of elements 32 of insulating material extend across the internal flanges and form a support for conductor bars 33 and 34 which are alternately disposed and spaced relative to each other.

The bars 33 are joined by a conductor 35 on the lefthand side of the figure while a conducting bar 36 joins the conductors 34 on the opposite end thereof. The outer conductor bar 33 is joined to a flexible shunt 37 while a similar shunt 38 is joined to the outermost conducting bar 34. A pair of metal sleeves 39 project through the floating element 28 and are sealed thereto. A shouled insulating sleeve 41 is disposed within the sleeves 39 in which the end 42 of supporting links 43 project. The shunts 37 and 38 are welded, brazed, soldered, or otherwise joined to the end of the element ends 42 and in this manner the supporting elements 43 form the conductors for the current delivered to the alternately disposed pairs of bars 33 and 34.

The opposite end of the elements 43 are pivoted in insulating blocks 45 which are mounted on a cover plate 46 which encloses the opening 47 in the end wall of the element 22 which is enclosed by the cover plate. Terminals 48 and 49 are mounted on and insulated from the cover plate 46 and joined by flexible shunts 51 to the end portions 52 of the elements 43. A bar 53 is slidable on the elements 43 and is provided on the ends with clamp screws 54 by which the bar is positioned on the elements. The entire unit 13 with the insulating bar 53 and elements 43 are removable through opening 47 in the end wall of the radiator 12 when the cover plate 46 is disconnected therefrom. The cover plate 46 is provided with a flange 55 which is drawn against a sealing gasket 56 by a plurality of screws 57 to seal the opening.

When the radiator is to be operated, water is placed in the well 23 and current is conducted to the elements 33 and 34 by leads attached to the terminals 48 and 49. The bar 53 is adjusted on the elements 43 to regulate the depth to which the elements 33 and 34 are immersed. This regulates the rate of steam generation and the rate of current consumption which varies therewith. Very little, if any, steam generation is produced

when distilled water is employed and it was found that water which contained salts and minerals functions in a very satisfactory manner. The addition of such elements may be made to the water to increase the steam generating action. Care must be observed, however, not to employ such salts and minerals which will react on elements 33 and 34 and cause them to corrode.

In case the steam pressure developed by the unit 13 in the radiator becomes excessive, a blow-off valve 58 releases the pressure within the radiator. The radiator is entirely portable, and may be moved to any position in the room and plugged directly into a wall socket in the normal lighting circuit. If at any time the steam generating unit fails to function, or functions inefficiently, it may be removed by removing the screws 57 which release the plate 46 from the side of the radiator in which the opening 47 is provided through which the entire unit 13 may be removed.

In Fig. 5 the radiator wall is illustrated in section to disclose the porcelain enamel coating 40 which is applied thereto by assembly. The porcelain enamel covers all of the metal of the radiator, the inside and outside thereof, so that the metal is completely insulated from the electric current. The fact that the porcelain enamel is a less conductor of heat than the metal does not enter into the efficiency of operation of the device, since the heat can not be conducted away from the radiator and can only be dissipated in the room in which the radiator is operating. The porcelain enamel, while providing a pleasing appearance to the radiator, eliminates the danger of shock to one coming in contact with the radiator when the insulation in the circuit fails and the current is conducted to the radiator metal. The porcelain enamel prevents such charging of the metal with the current of the circuit and renders the radiator and like devices acceptable to the underwriters.

Referring to Figs. 6 and 7, I have illustrated a steam generating unit 61 having a float provided with insulating sleeves 41 through which conductors 62 project for connection to an electric circuit. Insulating elements 63 on the float 28 project over pins 64 for locating the float relative to a removable bottom plate 65 from which the pins project. The bottom plate closes an opening 66 when secured against a sealing gasket 67 by a screw 68. The float 61 functions in a manner similar to the unit 13 and differs therefrom in that it is retained in position by the pins 64 instead of the pivoted elements 43. The buoyancy of the float 61 may be varied by changing the weight of the elements 63 at the sides of the floating chamber.

In Figs. 8 and 9, I have illustrated a further form which my steam generating device may assume. The device 71 embodies a circular float 72 on which a pair of conductors 73 and 74, which are retained spaced from each other and wound spirally, are secured. The conductors may be made of wire, but are herein illustrated as being made of a strap material. The inner ends of the conductors are joined to the insulated leads 75 and 76 which are connected to a pair of terminals 77 on the plate 78 which encloses an opening 79 in the wall of the radiator or other unit. An insulating gasket 81 seals the plate to the wall when secured in position by screws 82.

A cylinder 83 is mounted through the plate 78 having a vent cap 84 on the end which is provided with an aperture 85. An aperture 86 is provided in the wall of the cylinder on the outer

side of the plate 78. Within the cylinder a piston 87 is mounted having a piston rod 88 connected to an arm 89 of a bell crank 91. The bell crank is pivoted on an arm 92 projecting from the inner end of the cylinder 83. An arm 93 of the bell crank has a bifurcated end 94 which receives a pin 95 projecting from the bottom of the float 72 and engages a laterally projecting pin 96 on the pin 95. As the pressure builds up within the device, the piston 87 is moved outwardly in the cylinder 83 which thereby permits the float to rise in the water and reduces the amount of steam generation. Should the pressure become too great, the piston moves outwardly a sufficient amount to have an aperture 97 thereof mate with the aperture 86 in the cylinder to vent the steam on the inside of the device to atmosphere. As soon as the pressure within the device drops, the pressure of the atmosphere moves the piston inwardly of the cylinder thereby operating the bell crank in a counterclockwise direction to draw the float further into the water to thereby increase the rate of steam generation. The opening 79 is sufficiently large to permit the entire device 71 to be withdrawn therethrough when the plate 78 is released from the side wall of the device.

In Fig. 10, I have illustrated a device 98 which comprises a receptacle 99, a cover 101, and a steam generating device 102 of a type herein illustrated to show uses of the device other than for heating a radiator. The device illustrated in Fig. 10 may be a humidifier for delivering steam to the atmosphere of a room or may be used as a sterilizer for sterilizing instruments, towels, or the like. The steam generating unit readily lends itself for the generation of steam rapidly and for short periods of time such as for sterilizing and humidifying.

Having thus described my invention, what I claim by Letters Patent is:

1. A steam generating unit including a float, a plurality of bare conductors of one lead, a plurality of bare conductors of another lead alternately disposed relative to said first conductors, said conductors being mounted directly upon said float for partial immersion in a liquid, a pair of leads respectively connected to said alternate conductors, and means in addition to said leads for positioning the float while permitting it to freely move vertically upon a liquid.

2. A steam generating unit including a float, a plurality of bare conductors of one lead, a plurality of bare conductors of another lead alternately disposed relative to said first conductors, said conductors being mounted directly upon said float for partial immersion in a liquid, a pair of leads respectively connected to said alternate conductors, means in addition to said leads for positioning the float while permitting it to freely move vertically upon a liquid, and a weight shiftable on said pair of leads for varying the weight of the float for regulating the degree of immersion of the conductors.

3. In a device in which steam is to be generated, a float, a plurality of spaced alternate pairs of conductors mounted on said float, means for positioning said float within said device, a pair of leads joined to said alternate pairs of conductors, respectively, and extending to the exterior of said device, said device having an aperture through which said float and conductors are removable, and a plate for covering said opening.

4. In a device in which steam is to be gener-

ated, a float, a plurality of spaced alternate pairs of conductors mounted on said float, means for positioning said float within said device, a pair of leads joined to said alternate conductors, respectively, and extending to the exterior of said device, said device having an aperture through which said float and conductors are removable, and a plate for covering said opening, said positioning means being secured to said plate.

5. In a device in which steam is to be generated, a float, a plurality of bare conductors of one lead, a plurality of bare conductors of another lead alternately disposed relative to said first conductors, said conductors being mounted on said float for partial immersion in a liquid, a pair of leads each joined to a set of alternate conductors, a plate covering an opening in the device, and an arm pivoted to the plate and to said device for controlling the position of the float.
10. In a device in which steam is to be generated, a float, a plurality of bare conductors of one lead, a plurality of bare conductors of another lead alternately disposed relative to said first conductors, said conductors being mounted on said float for partial immersion in a liquid, a pair of leads each joined to a set of alternate conductors, a plate covering an opening in the device, and an arm pivoted to the plate and to said device for controlling the position of the float.
15. In a device in which steam is to be generated, a float, a plurality of bare conductors of one lead, a plurality of bare conductors of another lead alternately disposed relative to said first conductors, said conductors being mounted on said float for partial immersion in a liquid, a pair of leads each joined to a set of alternate conductors, a plate covering an opening in the device, and an arm pivoted to the plate and to said device for controlling the position of the float.
20. In a device in which steam is to be generated, a float, a plurality of bare conductors of one lead, a plurality of bare conductors of another lead alternately disposed relative to said first conductors, said conductors being mounted on said float for partial immersion in a liquid, a pair of leads each joined to a set of alternate conductors, a plate covering an opening in the device, and an arm pivoted to the plate and to said device for controlling the position of the float, and a weight movable along said arm for regulating the degree of immersion.

25. In a device in which steam is to be generated, a float, a plurality of alternately disposed conductors mounted on said float, a pair of leads each joined to a set of alternate conductors, a plate covering an opening in the device, an arm pivoted to the plate and to said device for controlling the position of the float, a cylinder in said plate, a piston in said cylinder connected to said arm which is operated by the movement of the piston produced by the change of pressure within the device.
30. In a device in which steam is to be generated, a float, a plurality of alternately disposed conductors mounted on said float, a pair of leads each joined to a set of alternate conductors, a plate covering an opening in the device, an arm pivoted to the plate and to said device for controlling the position of the float, a cylinder in said plate, a piston in said cylinder connected to said arm which is operated by the movement of the piston produced by the change of pressure within the device.
35. In a device in which steam is to be generated, a float, alternate conductors supported by said float in a position to be immersed in a liquid, a pair of arms pivoted to said float while being insulated therefrom, a pair of leads joined to said arms and to said alternate conductors, respectively, said arms positioning the float upon the liquid while functioning as leads for the current conducted to said conductors.

40. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.

45. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a plate for
50. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.
55. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.
60. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.
65. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.
70. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.
75. In a device in which steam is to be generated, a float, alternate conductors supported by said float in a position to be immersed in a liquid, a pair of arms pivoted to said float while being insulated, a pair of leads joined to said arms and to said alternate conductors, respectively, said arms positioning the float upon the liquid while functioning as leads for the current conducted to said conductors, a place for enclosing an opening in the device sufficiently large to permit the unit to be removed therethrough, means on said plate for pivoting said arms, conductors on the ends of the arms adjacent to said plate, and terminals on said plate to which the conductors are secured.

enclosing an opening in the device sufficiently large to permit the unit to be removed therethrough, means on said plate for pivoting said arms, conductors on the ends of the arms adjacent to said plate, terminals on said plate to which the conductors are secured, and a weight secured to said arms which is adjustable therewith for regulating the degree of immersion of the float and the conductors.

11. A radiator comprising a plurality of pan like stampings having a closure plate forming chambers, said stampings and plates having flanged openings which are joined together when the chambers are built up horizontally on each other with the chambers spaced apart and communicating with each other through said flanged openings.

12. A radiator comprising a plurality of pan like stampings having a closure plate forming

chambers, said stampings and plates having flanged openings which are joined together when the chambers are built up horizontally on each other with the chambers spaced apart and communicating with each other through said flanged openings, and a steam generating unit mounted in the bottom of the radiator.

13. A radiator comprising a plurality of flat pan-like stampings having a closure plate permanently secured thereto, forming a chamber, said chamber and closure plate having aligned openings with flanges thereabout extending outwardly therefrom, said flanges being secured together when the chambers are built up horizontally in spaced relation to each other, the space between said chambers being disposed at a slight angle to create a convection flow of air across the chambers when heated.

ALFRED H. HABERSTUMP.
